UNITED STATES PATENT OFFICE.

GEORG BIEDERMANN, OF STADTLENGSFELD, GERMANY, ASSIGNOR TO THE ROSENTHAL CHINA CORPORATION, OF NEW YORK, N. Y.

DESIGN FOR A CHINA PLATE OR SIMILAR ARTICLE.

Application filed April 20, 1923. Serial No. 5,877. Term of patent 7 years.

To all whom it may concern:

Be it known that I, GEORG BIEDERMANN, a citizen of Germany, residing at Stadtlengsfeld, Germany, have invented a new, original, and ornamental Design for a China Plate or Similar Article, of which the following is a specification, reference being had to the accompanying drawing, forming part thereof.

Figure 1 shows the ornamental border in enlarged detail; and

Figure 2 shows the new design for a plate, the ornamental border shown being repeated throughout the circumference of the plate.

I claim:

The ornamental design for a china plate or similar article as shown.

In testimony whereof I affix my signature.

GEORG BIEDERMANN.
